UNITED STATES PATENT OFFICE.

ALBERT C. FISCHER, OF CHICAGO, ILLINOIS.

FLASHING FOR ROOFS OR THE LIKE.

Application filed January 24, 1927. Serial No. 163,052.

My present invention relates in general to roofs and the like weatherproof coverings, and has particular reference to a so-called flashing for sealing and anchoring the end 5 of roof coverings and gutters at their junction with walls, chimneys and other terminals or obstructions.

The primary object of the invention is to provide means for effecting a positive 10 weatherproofing seal where the roof covering or gutter terminates alongside of walls, chimneys and the like locations.

Various expedients have been carried out to effect a weatherproof seal for the roof 15 covering, some of which, while effective for all practical purposes, require considerable effort to build. Others more easily made are not always as effective as they should be, and very often unsightly.

With my invention I can produce not only 20 a positive seal, so to speak, but one which will be unusually neat in appearance, easy to install and cheap to produce.

In the accompanying drawing, which illustrates 25 several embodiments of the invention Figure 1 is a perspective view of a portion of a wall showing a roof covering adjacent thereto, and illustrating the application of the invention.

Figure 2 is a perspective view in detail 30 of one part of the flashing strip.

Figure 3 is a perspective view in detail 35 of a companion part of the flashing strip.

Figure 4 is a view in cross-section showing 40 one way of anchoring the roof covering in the flashing strip.

Figure 5 is a similar view showing a 45 slightly modified way of anchoring or securing the roof covering in a flashing strip; and

Figure 6 is a view in cross-section showing 50 a similar modified form of flashing strip.

Referring now to the drawing in detail. For the purpose of illustration I have shown 55 a brick wall 5, 6 representing a roof with a flexible covering 7 therefor. The difficulty heretofore experienced has been to make some kind of a positive seal for the termination of the covering 7, so as to realize a completely sealed waterproof covering for the roof.

According to my invention I propose to use practically a two-part flashing strip, consisting of a base section 8 and a cover 55 section 9. In Figure 3 these parts 8 and 9 can usually be made in elongated strips of a

length suitable for the purpose, with their ends adapted to abut one another so that several of the sections may be used to develop a flashing strip along the side of a 60 relatively long wall or the like. As shown in Figure 1 the flashing strip is installed as an insert, so to speak, in a brick structure. For this purpose it would be desirable to make the depth of the base 8 equal to that of 65 the depth or thickness of an ordinary building brick. The width of the flashing when the cover 9 is applied to the base 8 should be equal to that of half of a brick, so that the flashing may be installed in the brick 70 structure without special arrangements. In other words it would simply take the place of the bricks for the length of the wall required for the flashing.

The base 8 is made with a modified rab- 75 beted or mortised edge, made to accommodate the cover 9, so that the concave under- side 10 of the cover 9 will fit over the convex surface 11 of the base, and with the vertical side 12 of the cover fitting against the ver- 80 tical edge 13 of the base. This makes up a mortised joint. These two parts of the flashing strip may be conveniently and cheaply made from an extruded, fibrated asphalt composition. In other words, the 85 strip is made up of sections 8 and 9. The sections when joined should have some qualities of compressibility, although rigid and strong enough to enter into the wall con- struction without interfering with the sup- 90 porting qualities of the brick work. I prefer- ably make the flashing strip of fibrated asphalt composition in order to obtain com- pressibility and waterproofing qualities of 95 the flashing, and also for cheapness and convenience in manufacture.

In installing the flashing the brick work will be carried on up to where the flashing is to be installed, then the base 8 may be in- serted in its proper position and the brick 100 work carried on as required. When the time comes to lay the roof covering 7 the edge of the same may be laid over the base of the flashing, and the cover 9 then inserted and hammered, or otherwise forced into 105 place. To securely anchor the end of the covering in the flashing, nails or other impaling means 14 may be employed as shown in Figure 4. This impaling means will pass thru the inserted end 71 of the covering and 110 pass thru the cover 9 into the base 8.

As shown in Figure 5 I may use a layer

or coating of mastic, or the like, 15 on opposite sides of the inserted edge of the covering to effect a more positive seal if desired. The impaling means 14 may or may not be used in this combination.

5 In Figure 6 I have shown dove-tailed slots 16 in the underside and top of the base 8, and in the top of the cover 9. The purpose of these slots is to interlock with 10 the plaster or mortar of the brick work so as to hold the flashing strip in place. If using a cover 9 with slot 16 therein it would not be altogether practical to insert the cover 9 after the brick work had been carried beyond the flashing strip. For this 15 reason it would be more desirable in using this form to terminate the brick work at the flashing and install and lock the flashing in place before carrying the brick 20 work on.

As will be seen from Figure 1 I am enabled to develop an exceedingly neat and practical flashing, and particularly one which makes a most effective weatherproof 25 seal between the roof covering and the wall, or other surfaces presented at right angles thereto. The flashing is easy to install, easy and cheap to make and, as stated, unusually effective.

30 I claim:

1. A flashing of the class described, comprising separable companion members adapted to enter into engagement with one another to provide a joint between them for the reception of the edge of a roof covering, said members being formed of a homogeneous mixture waterproofing binder and fiber.

2. A flashing of the class described, comprising separable companion members adapted to enter into engagement with one another to provide a mortised joint between them for the reception of the edge of a roof covering, said members being formed of a homogeneous mixture of waterproofing binder and fiber.

3. A flashing of the class described, comprising separable companion members, said members comprising strips of pre-formed, fibrated, bituminous composition, and adapted to enter into engagement with one another to provide a joint between them for the reception of the edge of a roof covering.

4. A flashing of the class described,

comprising extruded strip-like companion members formed of a fibrated, bituminous composition, and adapted to enter into engagement with one another to provide a mortised joint between them for the reception of the edge of a roof covering.

5. A flashing of the class described, comprising a pair of companion strip-like members, each of said members being formed of a homogeneous mixture of waterproofing material and filling material with complementary joining faces to provide a joint for the reception of the edge of a flexible roof covering, the formation of the edges of the joint adapted to crimp the edge of the roof covering in the joint, and means for holding the members together substantially as and for the purpose described.

6. A preformed flashing of the class described, comprising separable, preformed, strip-like associated members adapted to enter into engagement with one another to provide a joint between them for the reception of the edge of a roof covering, said members being formed of a mixture of waterproofing binder and filling material.

7. A flashing of the class described, comprising preformed, strip-like, associated members adapted to be brought into engagement with one another to provide a joint therebetween for the reception of the edge of a roof covering, said members being formed of a homogeneous mixture of waterproofing material and a reinforcing filler and binder.

8. A flashing of the class described, comprising two preformed strips of a homogeneous mixture of bituminous material and filling material, said strips having associated faces adapted to interfit so as to hold therebetween the edge of a sheet of roof covering, said strips when associated being rectangular in cross-section.

9. A flashing of the class described, comprising two strip-like members of bituminous material adapted to be interconnected to receive therebetween the edge of a sheet of roof covering, said members having substantially dovetailed slots on their outer surface to interlock with the plaster or mortar of the adjacent brick work.

Signed at Chicago, Illinois, this 13th day of January, 1927.

ALBERT C. FISCHER.
